UNITED STATES PATENT OFFICE.

ELIJAH F. SPAULDING, OF BROOKLYN, NEW YORK, ASSIGNOR TO ARTEMAS WARD, OF NEW YORK, N. Y.

COIN-CONTROLLED VENDING-MACHINE.

1,189,303.

Specification of Letters Patent.

Patented July 4, 1916.

Application filed March 3, 1913. Serial No. 751,766.

To all whom it may concern:

Be it known that I, ELIJAH F. SPAULDING, a citizen of the United States, and a resident of Brooklyn, in the county of Kings and 5 State of New York, have invented certain new and useful Improvements in Coin-Controlled Vending-Machines, of which the following is a specification.

The invention relates to improvements in 10 coin-controlled vending machines, and it consists in the novel features, arrangements and combinations of parts hereinafter described, and particularly pointed out in the claims.

15 The object of the invention is to provide an entirely efficient and reliable vending machine, capable of ready manufacture and operation and adapted to be operated for ejecting goods only upon the introduction of 20 the proper coins to the machine.

The invention will be fully understood from the detailed description hereinafter presented, reference being had to the accompanying drawings, in which:

25 Figure 1 is a central vertical section on the dotted line 1—1 of Fig. 9 and partly broken away, of a vending machine embodying my invention, the operative mechanism of the machine being shown in its normal condition and the method of introducing the coins being indicated; Fig. 1 also illustrates by 30 dotted lines the return of coins of improper dimensions to the purchaser; Fig. 2 is a detached top view of one of the goods ejectors, 35 there being one ejector for each vertical column of confections; Fig. 3 is a front view of a portion of the lower end of the multiple-column or section tray for holding the confections; Fig. 4 is a detached vertical 40 section through a portion of the operative mechanism and illustrates the relative arrangement of the parts thereof when a vertical section of the tray is empty and any coins introduced with relation thereto are 45 therefore to be returned to the purchaser;

Fig. 5 is a vertical section through the operative parts of the mechanism and illustrates the relation of said parts after a proper coin has been introduced to the machine to tilt 50 the goods ejector and the plunger or manually operative presser rod has been moved inwardly to a slight extent, the continued inward movement of said rod resulting in the goods ejector dislodging the lower piece

of confections; Fig. 5 shows the coin as just 55 released by the front end of the goods ejector so that it may fall into the coin-box or chamber, and also illustrates by dotted lines the hinged bottom of said box in its open position for the discharge of any coins that 60 may have accumulated thereon; Fig. 6 is a detached front elevation of about one vertical half of the casing-parts affording the coin-box and supporting a portion of the operative mechanism; Fig. 7 is a detached 65 top view of two main parts of the operative mechanism, one of said parts being stationary and the other slideable and having the push-rod secured thereto; Fig. 8 is a vertical section, partly broken away, through 70 the machine on the dotted line 8—8 of Fig. 9 and illustrates the mechanism in its operated position; Fig. 9 is a front elevation, partly broken away and partly in section, of the machine with the lower front casing member 75 and coin-slot plate omitted; Fig. 10 is a front elevation, partly broken away, of the machine, with the upper removable tray-concealing panel of the cabinet and the horizontal removable shelf below said panel and 80 above the operative mechanism omitted; Fig. 11 is a horizontal section through the coin-slot plate on the dotted line 11—11 of Fig. 10, and Fig. 12 is a vertical section 85 through the same and a vertical key thereon on the dotted line 12—12 of Fig. 11.

In the drawings, 16 designates the cabinet as a whole, said cabinet comprising a back 17, sides 18, an upper removable front 19 behind which the trays for the stacks of confection are located, a horizontal shelf 20 below the front 19 and removable or releasable by the removal of the said front, and a lower rigid front member 21.

22 designates the coin slot plate, 23 the vertical trays within which the pieces of confection 24 are stacked and from the lower ends of which said pieces are one after another during the operation of the machine, ejected, and 25 an interior curved plate serving as a chute for directing the ejected pieces of confection to a shallow cast tray 26 secured transversely across the front portion of the bottom 27 of the cabinet so that said pieces may be conveniently removed by the 105 purchaser or purchasers. The shelf or upper member 20 is held within grooves 28 formed in the opposite facing surfaces of

the sides 18, and said shelf is transversely grooved as at 29 to receive the lower edges of the front 19 of the cabinet, said front being at its upper end secured to the top 5 of the cabinet, not shown, by a lock in accordance with customary practice, and at its lower end being recessed in its opposite vertical edges, as at 30 (Fig. 9) to pass downwardly on rigid pins 31 projecting inwardly from the sides 18. When the shelf 20 and front 19 are in position and the upper end of the front 19 is secured to the top of the cabinet by a lock, said parts will be rigidly held and the lower end of the front 10 19 and pins 31 will prevent any withdrawal of the shelf 20.

The trays 23 for the stacks of confection are in general construction of customary character, as shown, and said trays, for the 20 purposes of my invention, are provided at their lower front edges with a connecting angle plate 32 affording an upper flange 33 by which the lower end of the trays may be rigidly secured to a stationary casting 25 34 (Fig. 7), the lower end of said plate 32 being recessed as at 35 (Fig. 3) to permit the passage therethrough of the rear ends of the goods ejectors, and said plate at opposite sides of said recesses being formed 10 with rearwardly turned flanges 36, to support the stacks of confection. The flanges 36 are only, preferably, at the lower front edges of the trays 23 and they are separated from each other so as only to support the 5 15 confectons at their opposite front end edges and permit the goods ejectors to pass between them. Upon each stack of confection I apply a weight 37 having a forwardly and downwardly projecting arm 38 whose lower 20 end will, when the confections have all been sold from a tray, pass into a position with relation to the goods ejector, as shown in Fig. 4, which will prevent the operation of the ejector and hold it in such position that 25 any coins delivered to the coin slot with relation to the empty tray will not become arrested within the machine but return to the purchaser, in the manner hereinafter explained.

Below the shelf 20 and in the rear of the coin slot plate 22 and front rigid member 21 of the cabinet is formed a chamber inclosing and protecting all of the operative mechanisms of the machine, with the exception 55 of the outer end of the operating rod or plunger 39, and within which chamber is also provided a box-like structure comprising a rigid plate 40 and hinged door 41 forming a receptacle 42 for the coins fed to 60 the machine in the purchase of packages therefrom. The plate 40 extends transversely between the sides of the cabinet and forms the top and front of the receptacle 42, while the hinged door 41 forms the bottom and rear wall of said receptacle. The

door 41 is hinged at its upper opposite edges, as at 43, and curves downwardly and forwardly to the lower front edge of the plate 40 so that when said door is allowed to open downwardly or to the position shown by 70 dotted lines in Fig. 1, the coins that may have accumulated thereon may easily descend into the tray 23 and be removed by the attendant. I provide means for locking the door 41 in its closed position, and these 75 means are only operable for opening the door after the front 19 and shelf 20 have been removed from the cabinet, it being customary to remove these two parts when replenishing the trays 23 and to at the same 80 time empty the cash box or coin receptacle 42. The means provided by me for locking the lower edge of the door 41 in its closed position shown in Fig. 1 comprise vertical 85 slidable bars 43, one being adjacent to the inner surface of each side of the machine, as shown in Fig. 9, and being mounted at their lower ends on screws 44 and at their upper portions being confined between the rear surface of the front 21 and studs or 90 screws 45, adjacent to which the bars 43 are formed with vertical recesses 46 which permit of a limited movement of the bars with relation to said pins or studs 45. The bars 43 are formed in their lower ends with the 95 slots 47 through which the screws 44 pass and which permit said bars to have a limited vertical movement on said screws. The lower rear edges of the bars 43 are formed with a lower rearwardly projecting lip 48 100 and an upper rearwardly projecting lip 49, and between these two lips of each bar the front edge of the door 41 is held. The upper ends of the bars 43 are pressed toward the pins or screws 45 by means of ordinary 105 wire springs 50 (Fig. 9), and hence the recesses 46 in said bars are enabled to coöperate with the pins or screws 45 to form latches for preventing downward movement of the bars 43 except when, upon the removal of the shelf 20, the upper ends of 110 said bars are pressed toward the front member 21 to unlatch them from the pins or screws 45. When it is desired to empty the coin receptacle 42 the upper ends of the 115 bars 43 will be correspondingly pressed toward the front member 21 to free them from the pins or screws 45 and then moved downwardly to the extent permitted by the slots 47 and screws 44 so that the lips 48 120 may take a position permitting the door 41 to swing downwardly to its open position. When it is desired to close and lock the door 41 the attendant may insert his hand through the lower front opening of the machine and press the door toward its closed position, thereby carrying the front edge of the door against the upper lips 49, where they project beyond the lower lips 48, and causing the bars 43 to move upwardly and 130

become latched by the pins or screws 45 and the lips 48 of said bars to ascend below the front edge of the door 41, thereby locking the latter in position. At the opposite lateral sides of the coin receptacle 42 are metal side plates 51 against which the bars 43 are arranged. The lower front edges of the plate 40 adjacent to the side plates 51 are recessed as at 52, Fig. 6, to permit of the vertical movement of the lips 49 with the bars 43.

The coin slot plate 22 is a vertical flat plate having a suitable number of coin slots 53, and at the inner edges of said slots inwardly projecting members 54 (Fig. 11) which serve as guides for the coins introduced through the slots and to prevent undue lateral movement of the coins during their insertion into the machine. The plate 22 might be a thick plate and thus render the separate guides 54 unnecessary, but I prefer that the plate 22 be of reasonably thin material and that the guides be made up, as indicated at 54, by rearwardly projecting portions thereof. The lower portion of the plate 22 extends downwardly at the inner vertical side of the front member 21 of the cabinet, as shown in Fig. 10, and said plate has cut in its upper central portion a vertical slot 55 denoted by dotted lines in Fig. 10, which permits on the introduction to the cabinet of the operative mechanism, the lowering to position, through said slot, of the plunger rod 39 to its operative position, said rod 39 when in its operative position being at the lower end of the slot 55, which lower end is rounded to conform to the shape of the rod 39 in cross-section. In order to secure the rod 39 at the base of the slot 55, I provide a key 56 which is grooved at its opposite edges to pass downwardly upon the facing edges of the slot 55, as shown in Figs. 10, 11, 12, and is recessed at that member thereof which is exterior to the plate 22, as at 57, to closely encompass the upper side of the plunger rod 39. The key 56 tightly fits upon the plate 22 but may be slid upwardly therefrom when necessary. The upper edge of the plate 22 and upper end of the key 56 are protected by the shelf or horizontal member 20 which, as shown in Figs. 1 and 8, is directly over the same.

The operative mechanism disposed between the plate 40 forming the top of the coin receptacle and the shelf 20 supporting the lower end of the front 19, comprises two main parts 34 (Fig. 7) and 58, both of which I prefer to make of cast metal. The part 34 is a stationary frame mounted upon the metal sides 51 and comprises a rear transverse bar 59 and side bars 60 which project forwardly nearly to the vertical latch bars 43 and are grooved in their facing edges, as at 61, to form supports and guides for the part 58 which is a slide, to

which the plunger rod 39 is secured, said rod 39 being hollow and containing the forward end of a spring 62 which acts to normally maintain the slide 58 at the outer ends of the guides 61 when in the position shown in Figs. 1 and 7. The rear end of the spring 62 has a bearing against the transverse member 59 of the frame 34. The slide 58 is formed with a hub 63 in which the rear end of the tubular plunger rod 39 is secured. The frame 34 constitutes a fixture upon which the lower end of the trays 23 may be supported and upon which the slide 58 and parts carried thereby may have their movements when pushed inwardly by the plunger rod 39 or outwardly by the spring 62. Aside from affording a support for the trays 23 and a support and guide for the slide 58, the frame 34 has secured to it in line with the coin slots stripper plates 85 or ejectors 64, these ejectors being rigidly secured at their rear ends to and below the transverse member 59 of the frame 34 and extending forwardly between sections 65 carried by the slide 58. The strippers or ejectors 64 are flat plates extending on edge and rigidly held at their rear ends in the member 59 of the frame 34, and said strippers are stationary and operate only when the slide 58 is pushed inwardly and it is necessary for said strippers to eject something from between the sections 65 which are rigid with the slide 58.

The sections 65 correspond with each other and are in the form of vertical plates 100 separated from each other and rigid at their front portions with the lower side of the slide 58, and said sections form between them the passages for the coins fed to the machine. Since in the present instance there are four of the trays 23 and four coin slots 53, the slide 58 is formed with four pairs of the plates 65, and these plates in outline are clearly illustrated in Figs. 1, 5, 7 and 8. The plates or sections 65 depend downwardly from the slide 58 and extend slightly forwardly of the front edge of said slide, which front edge is slotted, as at 66, to cooperate with the forwardly projecting portions of the plates or sections 65 and form 115 entrances for the coins fed to the machine to the spaces between said plates or sections 65. The slide 58 is formed directly in the rear of the slots 66 and consequently directly in rear of the coin slots 53 with vertical 120 standards 67 against which the coins fed through the slots 53 pass and which cooperate with the guides 54 on the coin slot plate 22 in guiding the coins downwardly to the entrance slots 66 of said slide 58, as 125 I represent in Fig. 1, in which a coin (numbered 68) is shown as having been introduced through a coin slot and against a standard 67.

The coins fed through the coin slots 53 130

travel between the plates or sections 65 and finally, if of the proper character, descend through openings 69 in the top 40 of the coin receptacle, as I represent in Fig. 5, wherein the coin is numbered 68 correspondingly with the numbering of the coin 68 in Fig. 1. The pairs of plates 65 correspond exactly with one another and all of said pairs of plates are equipped with corresponding mechanisms. I will therefore describe the mechanism provided with one pair of plates 65, this mechanism comprising a pivoted dog or washer catcher 70 (Fig. 9) at the entrance to the slots 66 in the slide 58, a pivoted weight-tester 71 located between the plates 65 at their front portion below the washer catcher 70 and above the extreme lower main edges of said plates, and a goods ejector 72 which is pivotally mounted between the rear portions of the plates 65 on a pin 73 which passes through a slot 74 in said goods ejector, said goods ejector being of right-angular general outline and having a lower arm 75 which operates to temporarily arrest a proper coin fed to the machine, as I represent by dotted lines in Fig. 1, and an upper arm 76 having two upwardly extending branches 77 supporting two flat laterally extending flanges 78 which, at the proper time, are moved above the flanges 36 at the bottom of the tray 23 and against the lower piece of confection held in said tray for the purpose of ejecting the same. The goods ejector 72 is yieldingly held in its lower normal position shown in Fig. 1 by means of a small spring 79 flexed against it. The coins fed to the machine pass between the plates 65 of each pair and first tilt the washer catcher 70 to pass by it, then tilt the tester 71 to pass by it, and then enter the space, which is open at the bottom, between the lower arm 75 of the goods ejector 72 and the edge of a screw-head 80 where the coin, if of proper dimensions, is retained until the machine is operated by the rod 39. If the coin which passed downwardly between the arm 75 of the goods ejector and the screw-head 80 had been of improper dimensions, it would immediately instead of being arrested have passed downwardly and forwardly, as noted by the lower circles in Fig. 1, and escaped to the tray 26 without having enabled the operation of the goods ejector and without having entered the coin receptacle 42. The screw-head 80 is a part of a screw which is screwed into the forward edge of one of the plates 65 and acts as a gage in co-operation with the arm 75 of the goods ejector 72, in testing coins as to their dimensions, a coin of less than the predetermined dimensions being allowed to slip by said screwhead and pass to the tray 26, and a coin of proper dimensions being temporarily arrested between the goods ejector and screw-head 80. The screw-head or gage 80

may be adjusted inwardly or outwardly to the requirements of the coins used for purchasing from the machine.

The forward ends of the stripper plates 64 have downwardly extending members 164 against which the forward vertical edges of the ejectors 72 press when the slide 58 moves to its outward or forward position, as represented by the dotted lines in Fig. 1. The members 164 of the plates 64 serve, with the springs 79, to assure a predetermined position for the ejectors when the slide 58 is in its outer position and at rest, and the adjustment for the coins used for purchasing from the machine is made by the screw-head or gage 80.

When the slide 58 is in normal position the forward vertical edge of the ejector 72 is engaged by the rearward vertical edge of the depending member 164 of the stripper plate 64. This engagement causes the ejector 72 to assume the position shown in Fig. 1, against the action of spring 79. When in such position the major portion of the slot 74 in the ejector 72 is rearwardly of the pin 73. The inserted coin after passing the coin testing devices, drops between arm 75 and screw 80 and assumes the position shown in Fig. 1. Upon inward movement of the slide 58 carrying with it the plates 65, ejector 72, the screw 80 and the coin carried thereby, the ejector 72 is moved away from, and is relieved of the pressure of, depending member 164. When this occurs the spring 79 pressing against the ejector 72 at a point above the point of engagement between the coin and the ejector swings the ejector about the coin as a fulcrum with the necessary result that the flanges 78 are inclined or tilted to a position in which their rear edges are slightly above the horizontal plane of the front edges of the flanges 36 below the tray 23. This movement of ejector 72 when relieved of the pressure of member 164, under the action of spring 79 and about the coin as a fulcrum, is permitted by reason of that portion of slot 74, which is rearwardly of pin 73, as above set forth.

The continued inward movement of the slide 58 and plunger 39 causes the flanges 78 of the ejector 72 to be carried above the flanges 36 and against the bottom piece of confection in the tray 23, with the result that the ejector is given a slight further tilting action sufficient to release the coin and also forces said piece of confection from the tray.

It will be seen on reference to Fig. 5 that the flanges 78 of the goods ejector are at a slight angle to the flanges 36 at the bottom of the tray, and this will be their position on their entrance above said flanges 36, and as said flanges 78 continue to ride above the flanges 36 of the tray, the flanges 36 will cause the goods ejector to have a slight further tilting movement which will assure the 123

release of any coin which may have been caught between the gage 80 and the arm 75 of the goods ejector. After the plunger 39 has been pushed inwardly to its full extent and the goods ejector has dislodged the lower piece of confection, the spring 79 will restore the goods ejector to its initial position shown in Fig. 1, and the spring 62 will move the plunger 39 and slide 58 outwardly to their initial position.

If instead of the coin 68 shown in Fig. 1 having been fed to the machine, a washer had been introduced to the coin slot, said washer would have been caught on the washer catcher 70 at the entrance to the space between the plates 65 and the slide 58. Then upon the inward movement of the plunger rod 39 the slide and goods ejector 72 will move inwardly, but since there was nothing to position the ejector 72 for use, no goods would be dislodged from the tray 23, but the inward movement of the slide 58 would carry the washer hanging from the washer catcher 70 inwardly far enough for the stripper plate 64 to be engaged by it and thereupon the stripper plate 64 would knock the washer from the washer catcher and said washer would descend to the front of the coin receptacle 42 and finally enter the tray 26, Fig. 1 by dotted lines showing discarded disks falling downwardly at the front of the coin receptacle 42 to said tray 26.

If an iron disk had been introduced to the machine, it would become arrested by the end of the magnet 81, and then upon the inward movement of the slide 58 the disk would be carried against the end of the stripper 64 and be discarded or ejected to the front of the coin receptacle 42 and fall into the tray 26.

If a disk too light in weight but not of magnetic material should be introduced to the machine it will be unable to tilt the rear end of the weight tester 71 downwardly so as to pass said weight tester, and such disk when the slide 58 is moved inwardly would be carried against the stripper 64 and ejected to fall into the tray 26.

If a coin lacking in proper diameter but of sufficient weight should be introduced to the machine, it will fail to be caught between the gage 80 and goods ejector 72, and hence would at once fall downwardly from between the plates 65 to the front of the coin receptacle 42 and pass to the tray 26.

The magnets 81 are rods which extend between the pairs of plates 65 and project flush through adjoining plates of said pairs, one rod 81 thus serving for two pairs of the plates 65.

I also provide means for compelling a full inward movement of the plunger rod 39 and slide 58 after it starts inwardly, and these means comprise a ratchet 82 which is cast at

about the center of the lower side of the slide 58, and a weighted pawl 83 which is pivotally mounted at the side of the upper end of a standard 84 rigidly secured upon and at about the center of the top of the plate 40 defining the top of the coin receptacle 42. When the slide 58 is moved inwardly its ratchet will pass over the upper end of the pawl (see dotted lines in Fig. 5) but, as will be understood, said pawl will prevent at such time any reverse or forward movement of the slide 58. After the slide 58 has been moved to its full rearward position, the ratchet 82 will have passed beyond the pawl 83 and then said pawl will turn to a vertical position; thereupon the slide 58 may move frontwardly, and on such movement the front end of the ratchet 82 will move against and tilt the pawl 83 to the reverse position to that shown in Fig. 5 and slide over the teeth of said pawl, but at the same time the pawl will prevent any return inward movement of the slide 58 until said slide has moved entirely outwardly to its initial position, upon reaching which the rack or ratchet 82 will have become carried frontwardly beyond the pawl 83 and the latter will turn to a vertical position immediately in the rear of said rack so as to compel a complete inward movement when the slide is started inwardly again.

During the sale of confections from a tray 23 the weight 37 will gradually settle downwardly and finally when the last piece of confection has been discharged from the tray, the weight 37 will become arrested on the flanges 36 and the vertical portion of the arm 38 will extend downwardly to the front of the upper portion of the goods ejector 72 or to the position illustrated in Fig. 4. It will be obvious that when the arm 38 is at the front of and engaging the goods ejector, said ejector will be held in an inoperative position. The weight 37 and arm 38 make their final descent as the last piece of confection is sold, and hence the arm 38 reaches the position shown in Fig. 4, while the ejector 72 is at its inward position in rear of said arm. Then when the slide 58 moves frontwardly again the upwardly extending portion of the ejector 72 moves against the lower end of the arm 38 and becomes arrested thereby, the ejector being arrested slightly in advance of its normal position shown in Fig. 1, as will be seen by the fact that the pin 73 is at the front end of the slot 74, so as to create sufficient clearance between the downwardly projecting arm 75 of the ejector and the gage 80 to permit proper coins to pass directly between the plates 65 and to the front of the coin receptacles 22 and thence to the tray 26 or, in other words, to return to the purchaser, the tray 23 having been empty and no goods having been delivered for the coin.

It is believed that the operation of the machine will be fully understood from the description hereinbefore presented, the method of emptying the coin receptacle 42 having been explained in connection with the description of the construction of said receptacle.

What I claim as my invention and desire to secure by Letters Patent, is:

- means tending to maintain said goods-ejector in its initial position, combined with a coin-box below the slide having an opening in its top to receive an arrested coin 5 from said plates when the slide has moved inwardly sufficiently for the coin to be released by the tilting of said ejector, and a guideway to without the machine for the passage of coins or the like not arrested between said plates against the goods-ejector.
6. A coin-controlled vending machine, comprising in combination a coin-slot plate having a vertical coin-slot therein, a tray for the goods to be sold, a horizontal slide 10 having a vertical standard (67) in line with said coin slot and depending plates forming between them a space to receive and permit the passage therethrough of a coin and open at its front end to admit the coin on edge, 15 a handle for operating the slide, a goods-ejector pivotally mounted between and carried by said plates and having a front de-

pending arm to be engaged by a coin and a flanged portion at its rear end to engage the lower piece of goods in the tray when 25 said end is tilted, means at the front of said plates to engage the front edge of and arrest the coin between said plates when the rear edge of the coin is engaged with said arm, and means tending to maintain said 30 goods-ejector in its initial position and adapted when the coin is in position to serve as a fulcrum for said arm, to tilt the rear end of said goods-ejector, provision being made for limited inward movement of the 35 slide in advance of the goods-ejector.

Signed at New York city, in the county of New York and State of New York, this 20th day of February, A. D. 1913.

ELIJAH F. SPAULDING.
